PRESSURIZED DISPENSING CONTAINER

Louis V. Nigro, Saugus, Mass., assignor to The Gillette
Company, Boston, Mass., a corporation of Delaware

Filed July 9, 1969, Ser. No. 18,127

Term of patent 14 years

Int. Cl. D9—01

U.S. Cl. D9—9

Fig. 1.

Fig. 2.

Fig. 3.

Fig. 4.

Fig. 5.

Fig. 6.

Fig. 7.

Fig. 8.

Fig. 9.

Fig. 10.

Fig. 11.

FIG. 1 is a perspective view of a pressurized dispensing container showing my new design;

FIG. 2 is a front elevational view thereof;

FIG. 3 is a side elevational view thereof;

FIG. 4 is a top plan view thereof; and

FIG. 5 is a bottom plan view thereof. The undisclosed side is substantially the same in appearance as the side shown. The undisclosed back is substantially the same in appearance as the front.

FIG. 6 is a perspective view of another embodiment of my new design;

FIG. 7 is a front elevational view thereof; and

FIG. 8 is a side elevational view thereof. The undisclosed side is substantially the same in appearance as the side shown. The undisclosed back is substantially the same in appearance as the front. The undisclosed top is substantially the same in appearance as that shown in FIG. 4. The undisclosed bottom is substantially the same in appearance as that shown in FIG. 5.

FIG. 9 is a perspective view of still another embodiment of my new design;

FIG. 10 is a front elevational view thereof; and

FIG. 11 is a side elevational view thereof. The undisclosed side is substantially the same in appearance as the side shown. The undisclosed back is substantially the same in appearance as the front. The undisclosed top is substantially the same in appearance as that shown in FIG. 4. The undisclosed bottom is substantially the same in appearance as that shown in FIG. 5.

I claim:

The ornamental design for a pressurized dispensing container, substantially as shown and described.
